UNITED STATES PATENT OFFICE.

FREDERICK T. CONLEY, OF BOSTON, MASSACHUSETTS.

HOT-PAN LIFTER.

1,320,318.

Specification of Letters Patent.

Patented Oct. 28, 1919.

Application filed May 18, 1917. Serial No. 169,545.

To all whom it may concern:

Be it known that I, FREDERICK T. CONLEY, a citizen of the United States, residing at Boston, in the county of Suffolk and State 5 of Massachusetts, have invented new and useful Improvements in Hot-Pan Lifters, of which the following is a specification.

The present invention has for its object to provide a simple, durable and practical 10 device for lifting and removing culinary vessels, such as pie plates, pans and other dishes, used for cooking purposes, and the said invention resides in the novel construction, combination and arrangement of parts 15 set forth in the following description and falling within the scope of the appended claim.

Figure 1 is a perspective view of the lifting device in pan clamping engagement, the pan being shown in dotted lines; and

Fig. 2 is an enlarged vertical section taken through one of the clamping jaws showing the manner of connecting the adjustable head with said jaws.

Referring more particularly to the accompanying drawing, in which like characters of reference refer to corresponding parts in the several views, 5 denotes the device generally adapted for lifting and 20 removing culinary vessels of various sizes from stoves, tables and the like. The lifting device embodies a pair of crossed tongs 6 and 7, each provided with a handle 8, a jaw and a shank, connecting the jaw with 25 said handle. The jaw 9 is provided in the active gripping face thereof with a transverse semi-cylindrical groove 11 and the outer wall of said groove being extended below the terminal of the opposite wall of 30 the groove, to provide the jaw with a transverse depending lip 12, and I desire for the sake of clearness to hereafter refer to the jaw 9 as the upper jaw. The active face of the lower jaw 10 is provided with a transverse 35 rectangular slot 13 for slidably associating with the jaw 10 a T-shaped gripping member 14, the purpose of such gripping member being to adapt the lifting device for 40 culinary vessels of various depths. A 45 facing plate 15 is secured to the jaw 10 and over the rectangular slot 13 thereof, and this plate to an extent serves as the rigid gripping face of the jaw 10. In other words, upon the use of the lifting device, 50 the depending lip 12 being flared in an outward and downward direction, will adapt

the same to engage with the inner circumference of the vessel and the facing plate 5 will contact with the outer facing or circumference of such vessel.

The T-shaped gripping member comprises a rectangular shank 16 formed with a slot 17 through which the pin 18 projects for connecting the gripping member in the slot of the lower jaw 10 for vertical adjustments, consequently, when desiring to lift a large culinary vessel, by grasping the lug 19 of the gripping member, the same may be forced in an outward direction and prevent any liability of the culinary vessel 60 dropping from between the jaws of the tongs. Upon the disengagement of the lifting device from the rim of the culinary vessel, the jaws will be automatically forced open through the influence of the spring 65 70 coiled about the pivot 21 of the tongs.

It will be noted upon reference to Fig. 2 that the upper edge of the lower member 7 is concave or transversely grooved at its extremity to coöperate with the groove 11 in 80 the lower edge of the upper member in fitting around the bead at the upper edge of a pan. The upper edge of the facing plate or the lower jaw is thus brought against the outer surface of the rim of the pan in direct 85 opposition to the overhanging lip 12 bearing against the inner surface of said rim so that a strong grip is obtained on the pan without buckling the rim.

From the foregoing description, taken in 90 connection with the accompanying drawing, the advantages of construction and the method of operation will be readily apparent to those skilled in the art to which the invention relates, and while I have described 95 the principles of operation of the invention together with the device which I now consider to be the best embodiment thereof, I desire to have it understood that the device shown is merely illustrative and that such 100 changes may be made when desired as are within the scope of the appended claim.

What is claimed as new is:—

As a new article of manufacture, a lifting device for pans, dishes and the like, embodying a pair of pivotally connected cross tongs each comprising a handle, an upper jaw formed on the end of one of said handles, a lower jaw of rectangular formation provided on the end of the other of said 110 handles and having a rectangular slot, a ser- rated facing plate secured to and in spaced

relation with the active face of the last mentioned jaw and covering the said slot, and a T-shaped member mounted in the slot of the lower jaw, the shank of the T-shaped member being provided with an elongated slot and being in length approximately the width of the facing plate, and a pin protruding through said facing plate and thence through the slot of the T-shaped 10 gripping member to prevent any accidental

displacement of the latter from its jaw and further serving to limit the outward movement thereof, the said plate forming a continuation of the head of the gripping member upon the adjustment of the same in a 15 direction toward and in abutting relation with the gripping member.

In testimony whereof I affix my signature.

FREDERICK T. CONLEY.
